UNITED STATES PATENT OFFICE

WILLIAM A. VOLLMER, OF KENOSHA, WISCONSIN, ASSIGNOR TO SIMMONS COMPANY,
OF NEW YORK, N. Y., A CORPORATION OF DELAWARE

CRIB

Application filed August 23, 1926. Serial No. 130,817.

This invention relates to cribs and more particularly to the mounting of one of the side guards whereby the guard may be moved from its effective position to permit free access to the interior of the crib. One object of the invention is to provide means for mounting one of the side guards whereby it may be easily moved from its effective position to a position beneath the bottom of the crib so as to permit free access to the interior thereof. Other objects of the invention are to provide means for mounting a side guard in its effective position which will not readily become disengaged by accident and which will not be readily disengaged by the occupant of the crib; to provide means for retaining the guard in effective position which will be self-locking but which may be readily unlocked by the operator; to provide means for supporting the guard in both its effective position and in its position beneath the bed bottom, and to provide means for guiding the guard to its said position beneath the bed bottom. Other objects are to provide such guiding means which will be simple and sufficiently strong to withstand careless or rough treatment to which it may be subjected and which will not readily become disarranged and inoperative; and generally to provide an improved structure of the above described class which will be simple to operate, comparatively strong and rigid and low in manufacturing cost. Other objects and advantages of the invention will become apparent when the following specification is considered in connection with the accompanying drawings, wherein I have illustrated a selected embodiment of my invention and wherein Fig. 1 is a side elevation of a crib embodying my improved structure; Fig. 2 is a plan of a portion of one of the latching means; Fig. 3 is an elevation of the means shown in Fig. 2; Fig. 4 is a section on the line 4—4 of Fig. 1, showing the side guard in its position beneath the bottom in dotted lines, and Fig. 5 is a section on the line 5—5 of Fig. 4. Referring now to the drawings, the crib comprises end frames 10 and 11, having corner posts 12—12 and 13—13 respectively, a side guard 14 extending between the corner posts 12 and 13 of the end frames and fixed in its position thereto, a bed bottom 15 of any suitable construction and a movable side guard 16 which is maintained in effective position between the corresponding corner posts 12 and 13 by means which will be more fully described hereinafter. The corner posts are preferably provided with suitable casters 17 at their lower ends to facilitate movement of the crib from place to place. As best understood from an inspection of Fig. 4, this invention contemplates moving the side guard 16 from its effective position, as shown in full lines, to an ineffective or inoperative position beneath the bottom of the crib, as shown at 16' in dotted lines. To hold the side guard 16 in effective position, a suitable latch means 18 is provided adjacent the top of the guard at each end thereof, which is adapted to cooperate with suitable means provided on the corresponding corner posts of the end frames. This latch in the present embodiment comprises a plate 19 secured to the corresponding corner post by suitable means such as screws 20, and provided with a stud 21, projecting therefrom and having a head 22. A member cooperating with the above mentioned studded plate comprises a member 23, also preferably of sheet metal, secured to the side guard by suitable means, such as screws 24, and having a portion 25 projecting outwardly in front of the plate 19 and provided with a hook portion 26, as best shown in Fig. 3. The hook portion 26 is adapted to engage or hook over the stud 21, and a locking member 27 is provided to prevent accidental disengagement of said hook member from said stud. The locking member 27 comprises a hook-like part pivotally mounted as at 28 on the portion 25 of the crib member 23 and having a hook end 29 which is adapted to swing on the pivot 28 to a position beneath the stud 21. The pivot 28 is preferably above and inside of the center of the stud 21, whereby gravity will be effective to cause the hook end 29 to assume its locking position, as shown in Fig. 3. The

hook end 29 is preferably shaped to provide a downward outwardly inclined portion 30 which will engage the under side of the stud 21 when the side guard is raised without swinging the locking member 27 on its pivot 28 so as to move the hook portion 29 thereof out of the way. It will be observed that when the side guard is raised, the inclined portion 30 of the hook member 29 will engage the under side of the stud 21 and will tend to more firmly hold the hook 29 in its locking position. To facilitate swinging the locking member 27 on its pivot 28 and thereby moving the hook portion 29 out of the way, I provide an outwardly extending lug 31, which may conveniently be engaged by the thumb or finger of the operator.

To hold the lower side or bottom of the side guard 16 in effective position and to guide the side guard to its inoperative position, I provide a guide rod 32 at each end of the crib, which guide rod is rotatably supported at its inner end by means of a bracket 33 secured to the adjacent end frame, and pivotally supported at its outer or front end by being bent upwardly, as indicated at 34, and inwardly, as at 35, said inwardly bent portion being rotatably disposed in a suitable aperture in the rail 36 which extends between the end frames of the crib and which constitutes a part of the bed bottom 15. The rod 32 may be prevented from moving forwardly and out of engagement with the bracket 33 at its inner end by suitable means, such as a collar 40 secured to the rod in back of the bracket 33. A bracket 37, having one leg 38 secured to the side guard, is provided with a leg 39 which is apertured to permit the passage of the guide rod 32 therethrough. The guide rod being pivotally supported at its outer end and rotatably supported at its inner end, may be moved laterally, in a substantially horizontal direction, to a limited extent, whereby extreme accuracy in positioning the guide rod and bracket is not necessary.

It will be observed that the lower edge or bottom of the guard 16 is held against displacement by engagement of the bracket 37 thereon with the guide rod 32. In order to support the side guard and to relieve the latch means 18 of the entire load, I prefer to provide a roller 41 rotatably mounted on the corner posts of the end frames beneath the bottom edge of the side guard, as best shown in Figs. 1 and 4.

When the side guard is to be moved from its effective position to the position shown in dotted lines in Fig. 4, the operator swings the locking member 27 out of the way of the stud 21 and lifts the side guard so as to clear the hook portion 26 of the latching member 25 from the stud 21. When the latch has thus been disengaged, the upper edge of the side guard may be pulled outwardly, the

guard swinging on the rod 32 at the bracket 37, which acts as a fulcrum, until the bottom edge of the side guard clears the rollers 41. The side guard may then be slid inwardly in a substantially horizontal position until substantially its entire width is disposed beneath the bed bottom, as shown. In replacing the guard to effective position, the operator may raise the guard to a position where the latch member 25 and locking hook 29 will be directly over the stud 21 and inside the head 22 thereof. The side guard may then be lowered until the bottom edge 42 of the locking hook 29 engages the top of the stud and will be thrown to one side due to its angular inclination, until the stud 21 is above said locking hook and engages the hook portion 26 of the latch member 25.

As above explained, the locking hook 29 will be caused to again assume its locking position by means of gravity. In practice I find that the side guard may be readily raised by gripping the lugs 31 on the locking hooks and swinging the locking hook on its pivot until the inclined edge 30 engages an edge 43 of the hook member 26 and is thereby limited in its swinging movement. Further lifting on the lugs 31 will then cause the entire side guard to be lifted as desired.

I have thus provided a movable side guard structure for a crib which may be easily moved from its effective or operative position to an inoperative position beneath the bottom of the crib, where it will be out of the way and permit free access to the interior of the crib. The means provided are simple in construction and consequently inexpensive and the latching means is not likely to be accidentally opened, nor is it apt to be unlocked by the occupant of the crib.

I am aware that various changes in the form and construction and proportion of parts may be made without departing from the spirit of the invention, and I therefore reserve the right to make such changes as fall within the scope of the following claim.

I claim:

In a crib, the combination of a pair of rigidly connected end frames, a bed bottom, an adjustably mounted side guard extending between said end frames and adapted to be moved to a position beneath said bed bottom so as to permit free access to the interior of the crib, releasable means adjacent the top of said side guard for locking said guard in effective position between said end frames, a guide rod extending transversely of the crib beneath the bed bottom, secured adjacent its inner end to a stationary portion of the crib and provided with an upwardly extending substantially vertical portion adjacent its outer end, said vertical portion being disposed inwardly of the inner face of said adjustable side guard and secured to an adjacent stationary portion of

the crib, a bracket having a portion extending inwardly from the inner face of said adjustable side guard and apertured to slidably receive said guide rod, thereby to permit sliding movement of said side guard 5 along said guide rod, and a roller rotatably mounted on a stationary portion of the crib, engaging the lower edge portion of the side guard when the latter is in effective position, 10 for supporting the guard in such position, said roller being also effective to guide the upper portion of the side guard in its movement from effective to adjusted position beneath said bed bottom.
